UNITED STATES PATENT OFFICE.

CLARENCE VICTOR JONES, OF TORONTO, ONTARIO, CANADA.

WINDOW-OPERATING DEVICE.

1,345,010.

Specification of Letters Patent. Patented June 29, 1920.

Application filed October 14, 1918. Serial No. 257,952.

To all whom it may concern:

Be it known that I, CLARENCE VICTOR JONES, a citizen of the United States of America, and resident of 230 Yonge street, 5 city of Toronto, county of York, Province of Ontario, in the Dominion of Canada, have invented certain new and useful Improvements in Window-Operating Devices, of which the following is a specification.

10 The invention relates to improvements in window operating devices as described in the present specification and illustrated in the accompanying drawings that form a part of the same.

15 The invention consists essentially of the novel means employed for securing a window in any desired position against the pressure of springs adapted to open same.

20 The objects of the invention are to provide a means whereby casement windows opening to the outside may be adjusted without the necessity of the operator reaching out of the window, to avoid displacement of screens and the like when adjusting 25 the window, to prevent damage caused by windows being blown open or shut and generally to provide a window operating device which will be inexpensive to manufacture, simple of operation, durable and 30 efficient.

In the drawings Figure 1 is a view of a window locked in an open position.

Fig. 2 is a cross sectional view on the line A—A of Fig. 1.

35 Fig. 3 is a detail view of a form of catch adapted to hold the operating chain to any desired position, one side of said catch being broken away to disclose the interior construction.

40 Fig. 4 illustrates a modified form of chain catch.

Like numerals of reference indicate corresponding parts in the various figures.

Referring to the drawings the window 1 45 is provided with two or more reverse hinges 2 adapted to exert an outward pressure on said window to open same, each of said hinges consisting of a pair of plates 3 from which extend inwardly from the top and 50 bottom thereof lugs 4 adapted to accommodate a pintle 5, a coiled spring 6 encircling said pintle between the lugs 4 and having its ends 7 projecting on to said plates to force same apart, and a pair of plates 8 55 pivotally secured to the plates 3 respectively by pins 9 and having screw holes 10 there-

through to permit of screwing the hinge to the window and frame.

In mounting a window in its frame the plates 3 of the hinges are forced together 60 against the pressure of the spring 6 and one of the plates 8 is secured on the inner frame 11 of the window and the other of said plates is secured to the inner side of the window sash so that said spring will 65 constantly exert pressure to open said window.

The outward movement of the window caused by the pressure of the spring hinges is controlled by means of a chain 12 secured 70 to the window sash in any desired location and operating through a catch mounted on the window frame, said catch consisting of a bracket 13 adapted to be secured on the inner side edge of the window frame and 75 having a strap portion 14 extending outwardly at right angles a short distance and provided with a short front wall or bar 15 and then turned upwardly parallel with said bracket, and an inwardly pointing curved 80 finger 16 pivotally mounted on a transverse pin 17 adjacent to the upper end of said portion 14 and having a shoulder 18 intermediate of its length projecting downwardly and forming with said wall 15 jaws 85 adapted to grip said chain and hold the window from further outward movement.

The finger 16 preferably projects considerably beyond the portion 14 and has its outer end 19 increased somewhat in width 90 thus forming a greater surface for engagement by the chain.

In the employment of the catch described above it is preferable to use a form of chain in which the links have narrow looped portions 95 20 terminating in widened flat ends 21, as shown in the drawings, so that the jaws will grip the flat portion in advance of the looped portion and thus effectually prevent the outward movement of the chain. 100

It will have been seen from the foregoing that to open the window it is only necessary to grasp the loosely hanging portion of the chain and by raising it upwardly lift the end of the finger 16 sufficiently to admit of the looped portion of said chain passing between the gripping jaws when the spring hinge will force the window open. When the window has opened sufficiently the operator simply has to drop the chain 110 and the finger immediately drops down and the chain is gripped as before. To close the

window it is only necessary to pull inwardly on the chain the required distance and then drop same.

In Fig. 4 a modified form of catch is shown in which the chain operates through a box-like structure 22 having its end adjacent to the window opening and its front end provided with a narrow slot 23 into which the reduced portion of a link is adapted to drop to prevent further outward movement. The same form of chain is used with this catch as with the first described catch but it is preferable to reverse the ends thereof so that the narrow looped portion 15 of a link will drop into said slot and the widened flat portion will abut the side walls of said slot.

To adjust the window it is only necessary to raise the chain from the slot 23 and allow the window to open, or to pull inwardly on the chain accordingly as to whether the window is to be opened or closed.

It will of course be apparent that when the window is covered by a screen it is only necessary to slot the frame of the screen to

accommodate the form of catch employed and the window may then be adjusted without interfering with said screen.

What I claim is:—

The combination of a window frame, an automatically opening window sash mounted therein, a chain connected to the sash for closing it, a bracket secured to the window frame and having a bar projecting outwardly therefrom to support the chain, a 30 clamping lever pivoted transversely above the chain in said bracket and having an intermediate ratchet tooth automatically engaging the links of the chain above said bar, the free end of the lever extending 35 longitudinally above the outer portion of the chain and adapted to be raised and released thereby when the outer portion of the chain is raised.

Signed at Toronto, Ontario, this 9th day 40 of August, 1918.

CLARENCE VICTOR JONES.
